UNITED STATES PATENT OFFICE

HENRY H. CUTLER, OF CHICAGO, ILLINOIS, ASSIGNOR TO THE CUTLER-HAMMER MANUFACTURING COMPANY, OF SAME PLACE.

SELF-STARTER FOR ELECTRIC MOTORS.

SPECIFICATION forming part of Letters Patent No. 625,246, dated May 16, 1899.

Application filed December 27, 1897. Serial No. 663,697. (No model.)

To all whom it may concern:

Be it known that I, HENRY H. CUTLER, a citizen of the United States, residing at Chicago, in the county of Cook and State of Illinois, have invented a certain new and useful Improvement in Self-Starters for Electric Motors, of which the following is a full, clear, concise, and exact description, reference being had to the accompanying drawings, forming a part of this specification.

My invention relates to a self-starter for electric motors, my object being to provide an improved and effectively-operating device for automatically controlling the starting of an electric motor.

In accordance with my invention in the preferred form I provide a circuit-controlling arm or element adapted to be moved over a series of contacts or terminals, the arm being arranged to move in one direction by gravity or its equivalent and in the other direction through the agency of a spring or other resilient device, an electromagnetic device being provided for placing the spring under tension.

In the preferred construction the main motor-switch is operated automatically through the agency of the core of the solenoid. I usually provide a shunt-circuit in which is included the solenoid and also a switch, whereby when the switch is closed circuit is completed through the solenoid, which is thereby caused to attract its core to close the main switch of the motor-circuit and at the same time place the coiled spring under tension to cause the resistance-bar to move over the rheostat-terminal, the movement being retarded through the agency of a dash-pot.

Referring to the accompanying drawings, Figure 1 is a view in elevation of the motor-starter of the present invention. Fig. 2 is a side view thereof. Fig. 3 is a view in elevation showing the circuit arrangement in diagram.

Like letters refer to like parts in the several figures.

The solenoid *a* is provided with a core *b*, through the hollow interior of which extends the coiled spring *c*, one end of which is attached to the end of the core, while the other end is attached to the resistance-bar *d*, provided with brushes upon the ends which move over the series of rheostat-terminals *d*, *d*², the

two brushes of the resistance-bar being electrically connected together. The core *b* carries at the upper end a pin *b*', which when the core is moved upward engages the switch-lever *e*, pivoted at *e*', and rocks the same upon its pivot to move the blade *e*² into engagement with the terminals *f*, *f*' and to move the blade *e*³ into engagement with the terminals *f*², *f*³. Upon the end of the blade *e*² is mounted a smaller blade or contact *g*, normally resting in contact with and closing circuit between the contacts *g*, *g*'. At the side of the contact *g*' is an insulating-block *g*². Secured to the resistance-bar *d* is the cylinder or tube *h* of a dash-pot, within which rests a piston *h*', carried upon a rod *h*², secured at the upper end to the support *h*³. The dash-pot retards the upward movement of the resistance-bar, while permitting the resistance-bar to freely move downward.

The circuit extends from generator *k* over limb *k*' to binding-post *k*², thence to brush or terminals *f*², and when the switch is closed over blade *e*³ to brush *f*³, thence to binding-post *k*³ by limb *k*⁴ through the armature *l* of the motor, then by limb *k*⁵ to binding-post *k*⁶, thence to the end terminal *d*' of the rheostat through the resistance-bar *d*, thence to the terminals *d*² upon the right through the resistances of the rheostat to limb *k*⁷ to brush or terminal *f*, blade *e*², terminal *f*', conductor *k*⁸, binding-post *k*⁹, thence by limb *k*¹⁰ back to the generator. The shunt-field coil *l*' of the motor is connected between the limb *k*⁴ and the limb *k*⁷. The coil of the solenoid *a* is included in the shunt-circuit across the mains and extends from binding-post *k*² through the contacts of switch *m* through the coil of the solenoid, thence to contact *g*', resistance *g*⁴ to contact *g*', to brush or terminal *f*'.

The operation of starting the motor is as follows: Normally the parts rest in the position illustrated in Fig. 1, the motor-circuit being open and the resistance being all included in the armature-circuit. By closing the switch *m*, as shown in Fig. 3, current from generator *k* passes over limb *k*' through the terminal *k*², thence through switch *m*, contact *g*', brush *f*', limb *k*⁸, binding-post *k*⁹, limb *k*¹⁰, back to the generator. Solenoid *a* is thus energized and attracts its core *b*, thus raising the same into the position illustrated

in Fig. 2 and places the spring *c* under tension. At the same time the pin *b'* strikes lever *e*, rocks the same, and closes blades *e²* and *e³* into engagement with their respective contacts. At the same time the contact *g* is moved into the position illustrated in Fig. 3, out of contact with solenoid *a* to cut down the current traversing the solenoid to a value just sufficient to maintain the core attracted 5 in its raised position. The resistance-bar *d* moves over the terminals *d'* *d²* gradually, being impelled by the coiled spring *c* and being retarded in its movement by the dash-pot. When the resistance-bar has reached the end 10 of its travel, it engages the brushes *n* *n* and the rheostat-resistance is entirely removed from the circuit. When it is desired to stop the motor, the switch *m* may be moved to open the circuit through the solenoid, and the 15 core *b* thereof is thus released and drops of its own weight, as also does the resistance-bar *d*, thus serving to cut the resistance into the armature-circuit. The arm *e* is moved back to its original position through the power 20 of the coiled spring *o*, thus opening the circuit through the motor.

Instead of employing gravity to return the parts to their original position other equivalent means may be employed—as, for instance, a light spring.

Instead of employing a switch *m* in the shunt-circuit with the solenoid for throwing the self-starter into operation the switch *m* may be omitted and the starting may be effected, for instance, by closing a switch in 35 the main motor-circuit, as *p* or *p'*, to thus send current through the shunt-circuit containing the solenoid, which actuates the same and throws the device into operation, as above 40 described.

While I have illustrated one specific form of my invention, it is apparent that the several parts may be otherwise disposed to accomplish the same general operation and result without departing from the spirit of my 45 invention.

Having described my invention, what I claim as new, and desire to secure by Letters Patent, is—

50 1. The combination with a circuit-controlling arm or element, of a series of contacts or terminals over which the same is adapted to be moved, means for moving the arm or element in one direction by gravity, or its equivalent, a spring, or other resilient device, for moving the arm in the opposite direction when under strain, and an electromagnetic device for placing the spring under strain, substantially as described.

60 2. The combination with a rheostat arm or bar, of a spring or other resilient device for moving the same to cut out resistance an electrical device for placing the spring under tension, and means for moving the rheostat arm 65 or bar to cut in resistance substantially as described.

3. The combination with a rheostat arm or

bar, of a spring or other resilient device for moving the same in one direction, an electrical device for placing the spring under tension, means for moving the rheostat arm or bar in the opposite direction, and a dash-pot or regulator retarding and controlling the movement of the bar in cutting out resistance, substantially as described. 70 75

4. The combination with a circuit-controlling arm or bar, of a spring or other resilient device for moving the same in one direction, a solenoid, the core of which is attached to the end of said spring and adapted when attracted to place said spring under tension, and means for returning the core and bar to their initial positions, substantially as described. 80

5. The combination with a circuit-controlling arm or bar, of a coiled spring for moving the same in one direction, a solenoid, and a hollow core therefor within which said coiled spring rests and to which the end of the spring is attached, and means for returning the core and the arm or bar to their initial positions, 90 substantially as described. 85

6. The combination with a rheostat arm or bar, of a spring or other resilient device for moving the same in one direction, an electromagnetic device for placing the spring under tension, an electric switch independent of the rheostat arm or bar adapted to be closed by said electromagnetic device, and means for returning the rheostat arm or bar and the switch to their initial positions, substantially 100 as described.

7. The combination with a rheostat arm or bar, of a spring, or other resilient device for moving the same in one direction, an electromagnetic device for placing the spring under tension, the coil thereof being included in a shunt-circuit with the motor to be controlled, substantially as described. 105

8. The combination with a rheostat arm or bar, of a spring or other resilient device for moving the same in one direction, an electromagnetic device for placing the spring under tension, the coil thereof being included in a shunt-circuit with the motor to be controlled, and means for introducing resistance into 110 said shunt-circuit after the spring has been placed under tension, substantially as described. 115

9. The combination with a rheostat arm or bar, of a spring or other resilient device for moving the same in one direction, an electromagnetic device for placing the spring under tension, the coil thereof being included in a shunt-circuit with the motor to be controlled, and a switch for opening and closing said 120 shunt-circuit to the passage of an operating-current, substantially as described. 125

In witness whereof I have hereunto subscribed my name in the presence of two witnesses.

HENRY H. CUTLER.
